CLOSURE OPERATING DEVICE

Martin C. Bersted, San Diego, Calif., assignor, by decree of court, to Julie Bersted widow of said Martin C. Bersted, deceased

Application February 25, 1935, Serial No. 8,105

12 Claims. (Cl. 16—185)

This invention relates to a spring controlled door hinge construction whereby a swinging door is yieldingly maintained either in open positions or in a closed position.

An object of the invention is to provide improved means for positioning the door per se with relation to its mounting means, thereby causing the door when closed to be more accurately positioned in the door opening, and also determining 10 more precisely the points at which the door will come to a stop when it is swung in either direction to an open position.

Another object of the invention is to provide improved means to gauge the relative positions 15 of an upper and a lower door hinge device in order that the mounted door will be held in a truly vertical position owing to the proper co-operation of said devices.

Still other objects and advantages reside in 20 the compactness, simplicity and low cost of manufacture of the claimed structures for swingingly supporting a door or other swingable closure element.

Other objects, advantages and features of invention may hereinafter appear.

Referring to the accompanying drawings, which illustrate what is at present deemed to be preferred embodiments of the invention,

Fig. 1 is a perspective view of the complete device, surface portions being broken away to disclose underlying structure, and portions of the door and of the casing being broken away to contract the view.

Fig. 2 is a perspective detail illustrating the 35 overhead mounting means in an exploded relation.

Fig. 3 is a vertical mid-section taken on line 3—3 of Fig. 1.

Fig. 4 is a plan view showing the cover removed 40 and showing certain parts sectioned on line 4—4 of Fig. 6.

Fig. 5 is a fragmental side elevation of the assembled spring-controlled structure upon which the door rests.

Fig. 6 is a vertical section of the structures 45 shown in the right hand portion of Fig. 4, taken on line 6—6 of the latter view.

Fig. 7 is a perspective view of the lower bearing member within which certain spring-controlled 50 parts operate.

Fig. 8 is a fragmentary bottom plan view of the structure shown in Fig. 6.

Fig. 9 is a perspective view of the cam block.

Referring in detail to the drawings, the door 11, 55 which swings adjustably in both directions, is

shown in Fig. 1 in an assembled relation to its lintel 12 and casing member 13. The threshold is omitted, but the base plate 14 of the control means is shown in the position it occupies when attached to a threshold or floor in its operative position.

Said base plate 14 is preferably rectangular, and it has a depressed foot portion 15 extending along three sides thereof thus elevating its body portion sufficiently to provide under it a clearance to receive a washer 16 and the peened over lower end of the tubular pivot pin 17. Upon the upper face of said base plate is superimposed the circular bearing plate 18 which has an upstanding peripheral flange 19. Said plate 18 is immovably clamped down against the plate 14 by means of the pivot pin 17 which extends therethrough, owing to the fact that said pin is furnished with an external annular bead or shoulder 20 which forcibly engages the upper surface of plate 18 when the lower end of pin 17 is peened over as shown.

Over the upstanding circular flange 19 of the fixed bearing plate 18 is turnably fitted the upper bearing plate or cap plate 21. Diametrically opposite portions of the flange of said cap plate are cut away thus providing room for the foot portion 22 of the L-shaped strap iron door supporting plate 23. This part 22 is apertured at 24 to engage turnably with the pivot member 17.

The cap plate 21 is furnished with a central circular rise 25 which cooperates with the top portion of the hollow pin 17 to form a raceway for the ball bearing members 26, this part of the bearing structure being completed by means of the headed central pivot pin 27, the upper end of which extends loosely thru the cap plate 21 and the lower end of which is peened over at 28.

Near the right side of the bearing structure as viewed in Fig. 6 the foot portion 22 of the door supporting member is furnished with a circular hole to receive the neck portion 30 of a downwardly extending stud 31. The top portion 30 of said neck is firmly peened down at 32 thereby holding said stud in a fixed relation to the part 22 of which it forms a part.

Farther to the right as seen in Fig. 6 the part 22 is preferably down bent at 35 where it emerges from the recess provided for it in the adjacent part of the cap plate 21.

Returning to the base plate 14, said plate has at its inner edge an upstanding flange 37 provided at its base with a horizontal slot 38 slidably receiving the follower plate 39. Supported by said flange 37, and projecting from the inner 55

face thereof is a horizontal guide rod 40, and the follower plate 39 has an upstanding end portion or arm 41 furnished with a bearing opening which surrounds said rod 40 with a working fit. 5 The door casing is bored out to receive the rod 40 and to provide a considerable clearance there-around. To the end of said rod is secured a nut 42 which forms an abutment for one end of an operating spring 43 coiled loosely around said 10 rod, the other end of said spring acting against the arm 41 of the slide 39.

The flange 19 and also a portion of the body of bearing plate 18 are cut away at 19c and 18c to provide a clearance for the free operation of 15 slide 39. A guide slot 14s is shown in base plate 14 within which travels with a working fit a depressed tongue 42 struck downwardly from the slide 39.

A cam member, shown as a block 45 is furnished 20 with a symmetrically located bearing aperture 45a (see Fig. 9) whereby it is mounted upon the bearing pin 17 with a working fit. Said block has a main central cam face 46. At one side of 25 said cam face is a cam projection 47 and at the other side thereof a like cam projection 48, there being a guiding surface 45x at each side of the main cam face 46 which directs the movement of the cam operating element 49 as it passes from the main cam face 46 to said cam projections. 30 When the guiding surfaces 45x are in an abutting relation with element 49, the door, in either position, is maintained partly ajar. Said cam operating element consists of an upstanding flange 49 with which the slide 39 is provided at 35 the end thereof which is adjacent to the cam block.

Describing more in detail the cooperation of the cam operating element 49 with the cam block 45, when said block is in engagement with the 40 main cam face 46 which maintains the door 11 in the closed position, and when said cam operating element rides over cam projection 48 to the extent indicated by dotted lines in Fig. 4 it holds the door open at one side of the door opening. 45 When said cam operating element rides over the cam projection 47 to the same extent it will hold the door open at the opposite side of the door opening. In this position the cam operating element 49 will engage both the cam projection 48 and the side portion of the arm 52 at that side of the block thus holding the door in a definite open position. In the assembled relation of the parts, the stud 31 is received, with considerable clearance, within a notch or recess 51 cut into 50 the edge thereof opposite to its central cam face 46. Or, said cam block may be regarded as yoke-shaped having arms 52 which pass astride the stud 31. Each of said arms has a screw hole extending therethrough which opens into the recess 51. Adjusting screws 53 and 54 are screwed into these holes the inner ends of said screws being engageable with opposite sides of the stud 31. By this construction, owing to the fact that the recess 51 is considerably wider than the stud 31 which it receives, by screwing in and out the screws 53 and 54 an adjustment may be effected whereby the door 11, in its closed position (due to the spring-pressed engagement of the flange 49 of slide 39 with cam face 46) may be properly centered. 70

The auxiliary cam faces 47 and 48 will be formed in the proper angular relation to the central cam face 46 in order that when the slide 75 flange 49 engages said auxiliary faces the door

will be maintained opened toward one side or the other to the desired extent.

The lateral projections 47 and 48 of the symmetrical, polygonal, plate-like cam block 45 exert a retarding action upon the door as it swings from either wide open position toward the closed position. When the invention is applied to a door which is furnished with a spring tending to close it with considerable force, this retarding feature is a valuable asset as it prevents a slamming or pounding action of the door against persons passing through the doorway. 10

The flange 19 of the bearing plate 18 has recesses 19x in its edge portion, and these recesses can be brought into register with like recesses 21x in the peripheral flange of the cap plate 21, thus affording admission openings for the tool whereby the screws 53 and 54 are adjusted. 15

The pivot pin 17 forms the lower hinge of the door. At the upper side of the door a combined 20 hinge plate and gage plate 60 is provided, said plate having a downwardly directed hinge pin 61 and with screw holes 62. With said hinge plate 60 cooperates a T-shaped socket member 63 having a socket portion 64 to receive said pin and 25 a wing at each side having a screw hole 65 to receive screws directed downwardly into the upper edge of the door. The door 11 is recessed as indicated in Fig. 3 to receive the socket member 64. 30

As viewed in Fig. 2, the center of the upper hinge pin 61 is located the same distance from the inner (left) end of the gage strip 60 as the center of the lower hinge pin 17 is spaced away from the back side of the upstanding flange 37 35 which lies adjacent the casing. This arrangement provides for mounting the door quickly in a truly vertical position, which is insured by abutting the left end of the gage strip 60 against the upper part of the door casing while the base plate 40 41 is attached to the threshold with its upstanding flange 37 lying adjacent to the lower portion of the door casing.

With regard to lubrication, the socket 64 of the upper hinge element forms an oil pocket. 45

It is to be understood that the form of my invention herewith shown and described is to be taken as a preferred example of the same, and that various changes in the shape, size and arrangement of parts may be resorted to without departing from the spirit of the invention, or the scope of what is claimed. 50

Having in this case described my invention, I claim:

1. In a device of the kind described, a cam member, mounted in a nearly fixed relation to a door to swing therewith, screw threaded adjustable means acting between said door and cam member to regulate their precise relative positions with respect to the swing of the door, upper and lower relatively turnable plates having peripheral flanges directed towards each other thereby forming a housing for said cam member, said flanges having recesses registrable with each other to provide openings for the admission of a tool to regulate said screw threaded means, and spring-impelled means co-acting with said cam member to yieldingly maintain said door in different parts of the path along which it swings. 60

2. In a construction of the kind described, a device attachable to a threshold and to a corner portion of a door to form a hinge element for said door, said device including an adjustable cam block having a plurality of straight faced cam 70 75

elements, and spring-pressed means engageable with the straight faces of said cam elements and arranged to yieldingly maintain a door in open, closed and partly open positions.

5 3. A cam device comprising a base plate attachable to a floor or threshold, a bearing plate superimposed upon said base plate, an upstanding pivot extending through said plates, said pivot having an annular shoulder extending therearound and a peened over lower end thus clamping said plates together, a cam block pivotally mounted upon said pivot in engagement with said bearing plate, means operatively connecting said cam block with a door to swing therewith, and 15 a spring-pressed follower operatively related to said cam block.

4. In a construction of the kind described, the combination, with a door; of a door positioning and retarding device attachable to said door and 20 to a threshold thereby forming a hinge element for said door, said device including a cam block having a cam face and a cam projection in spaced relation to said face, there being a guiding surface on said block at each side of said cam face, and 25 a spring actuated follower which is operatively related to said face, surface and projection, said follower when in engagement with said face holding the door closed, when engagement with said surface holding the door partly open, and when 30 it rides over said surface and projection holding the door completely open.

5. In a construction of the kind described, the combination, with a door; of a door positioning and retarding device attachable to said door and 35 to a threshold thereby forming a hinge element for said door, said device including a cam member having a plurality of cam elements and a spring actuated follower which is operatively related to said cam member and elements whereby said door 40 is maintained immovable in a plurality of different positions in the path in which it is swingable and is thereby retarded in its swing from fully opened position to fully closed position, said follower having a strap metal portion which has a tongue struck out from one face thereof, said door positioning device having a guide slot which 45 receives said tongue with a working fit.

6. In a construction of the kind described, a positioning and retarding device attachable to a door, said device including a cam member and elements whereby said door is maintained immovable in a plurality of different positions in the path in which it is swingable and is thereby retarded in its swing from fully opened position to 50 fully closed position and a spring actuated follower which is operatively related to said cam member, said device including also a housing furnished with a pivotal support for said cam member, and an elongated member which extends radially away from said pivotal support and forms a guide for said follower.

7. A cam device comprising a stationary base plate, a pivot secured to and upstanding from said base plate, a polygonal figured cam block turnably mounted upon said pivot, means to turn said cam block operatively related thereto in a radially spaced relation to its pivot, a guide rod extending

radially away from said pivot and supported by said base plate in a fixed relation thereto, a follower having a flange operatively related to the polygonal sides of said cam block and guided in its movements by said rod, said follower having 5 a tongue struck out from one face thereof and guided in its movement by said base plate, and a spring loosely coiled about said rod and positioned to oppose the action of said cam block upon the flange of said follower, all parts of said spring 10 encircling said rod.

8. In a device of the kind described, a multiple faced cam element, a spring pressed follower, and mounting means for said cam element and follower whereby said follower is maintained in a 15 swingable operative relation to said cam element to be thereby yieldingly arrested at five points of its swing, to hold a door in oppositely open, closed and opposite partly open positions.

9. The subject matter of claim 8 and said follower having a straight cam-engaging face, and said cam block having portions positioned for engagement with said follower face to maintain a door in opposite wide open positions, a central flat face engageable with said follower face to 20 hold a door closed, and a flat face at each side to hold a door partly open at each side of its closed position and to retard its swing through partly open positions.

10. In a device of the kind described, a plate- 30 like cam block of a symmetrical polygonal shape, the cam elements thereof occupying its edge portions, said block having a main flat cam face and a pivot aperture located adjacent to the central portion of said face, a lateral cam face at each 35 end of said main face, each said lateral cam face extending from said main face to a lateral cam projection of said block, said block having also corner portions to cooperate with said projections, a follower having a flat portion to cooperate with the cam portions of said block and at times to bridge the spaces between its corner portions and aforesaid projections, mounting means operatively relating said follower and cam 40 block, and means to urge said follower towards 45 said cam block.

11. A door positioning device including a cam member, a spring pressed follower, and means to mount said cam member and follower in an operative relation to each other, said follower having 50 a strap metal portion which has a tongue struck out from one face thereof, and said mounting means having a guide slot which receives said tongue with a working fit.

12. In a structure of the kind described, means 55 to yieldably arrest the swing of a door at a plurality of positions in the path in which it is swingable; said means comprising a multiple faced cam element turnably connected with a door, non-swingable means attachable to a threshold 60 and having a reciprocatory follower to cooperate with the faces of said cam element, a guide rod carried by said last recited means and positioned to extend laterally away from a door opening into a door jamb when the parts are in their operative 65 positions, and a spring upon said guide rod to act upon said follower.

MARTIN C. BERSTED.
